UNITED STATES PATENT OFFICE.

JOHN T. AUSTIN, OF HARTFORD, CONNECTICUT, ASSIGNOR TO AUSTIN ORGAN COMPANY, OF HARTFORD, CONNECTICUT, A CORPORATION OF MAINE.

ORGAN-ACTION.

1,167,130.

Specification of Letters Patent. Patented Aug. 11, 1914.

Application filed Aug. 3, 1911. Serial No. 342,195.

To all whom it may concern:

Be it known that I, JOHN T. AUSTIN, a citizen of the United States, residing at Hartford, in the county of Hartford and State of Connecticut, have invented new and useful Improvements in Organ-Actions, of which the following is a specification.

This invention is an improved action for musical instruments, especially for organs, for enabling the notes to be selectively sounded on different stops or registers of pipes.

The particular embodiment of the invention herein shown is adapted for use in an organ, the note sounding devices of which are controlled by perforated note sheets. In this arrangement the selection of the desired stop is determined by the difference in size of the successive perforations for the same note. These successive perforations operate through a single tracker duct, and a single primary pneumatic, the action of which under the control of the different sized perforations operates one or the other 25 or both of two valves or contacts controlling the two different pipes or registers of pipes to be sounded. The smaller perforations may be utilized to control the sounding of the notes in one stop or register of pipes 30 while the larger perforations may concurrently serve to sound the notes of a different stop or register of pipes. Thus both the solo and the accompaniment of a musical composition may be prearranged on the 35 same note sheet by means of the different sized perforations, the solo or melody notes being represented preferably by the larger perforations and the notes of the accompaniment by perforations of the smaller size.

Figure 1 of the drawings is a sectional end view of one of these improved actions adapted for electrical connections. Figs. 2 and 3 are fragmentary sectional end views similar to Fig. 1, showing the contact lever 40 in different positions. Fig. 4 is an underneath view showing the arrangement and relation of a series of these actions. Fig. 5 is an end view showing one of these improved actions adapted for pneumatic operation. Fig. 6 is an underneath view of a

series of the actions shown in Fig. 5. Fig. 7 is a side view and Figs. 8 and 9 are sectional end views showing these actions arranged for combined pneumatic and electric connections. Fig. 10 is a sectional end view of 55 a modified form of this improved action, also adapted for electrical connection. Fig. 11 is a sectional end view of another modification adapted for pneumatic connection. Figs. 12 and 13 are fragmentary end views 60 showing the pneumatic connections of Fig. 11 in different operating positions.

As illustrated in the drawings, these actions are attached to one side of an action bar 1, which in turn is suspended from or 65 supported by means of suitable cross cleats 2 from any convenient part of the frame of the organ. The primary ducts 3 connect with the primary pneumatics 4 and with a suitable vacuum chamber 5, which as herein 70 shown is on the opposite side of the action bar from the actions themselves, and extends lengthwise of the bar. Vents 6 of suitable size enable the primary ducts and pneumatics to be exhausted of the air after they 75 have been flushed. The ducts 3 lead through any suitable pipes 7 to their respective ducts 8 of a tracker board 9 or any other device suitable for admitting the air to flush the primary pneumatics at the desired time and 80 for the required period, perforated note sheets 10 being commonly employed for this purpose, in conjunction with the aforesaid tracker board.

One of the characteristics of this invention is the novel arrangement whereby the action is operated in a two-phase movement under the control of different volumes or pressures of air admitted through the tracker ducts, a light volume or pressure 85 serving to impart to the action its first-phase movement, the stronger impulse or larger volume serving to impart the second-phase movement, these two phases of movement operating different pipes, generally 90 for the same note in different registers or stops. These different impulses of the air may be admitted through two different ducts of the tracker board, using a forked 95 connection with the duct tube 7. But they 100

are preferably admitted through a single duct or duct tube, by perforations in the note sheet, of different sizes, but following each other in the same path, so as to register successively with the same duct, being pre-arranged to follow each other in the order required for sounding the respective desired notes, as shown in Fig. 4. Each of the tracker ducts 3 leads to a primary pneumatic 4, which in the embodiment herein shown consists of a diaphragm or pouch. These primary pneumatics are preferably staggered, being grouped, as shown in Figs. 4 and 6, in alternately reversed succession, in order to get the different key actions closer together, while providing for each action a diaphragm or pouch of ample size. Each diaphragm is attached to or operates upon a double acting pallet operating or contact closing member 14, which for conciseness and convenience will herein be termed a "lever."

In order to enable the levers and their connections to be readily examined and adjusted even when the organ is in full operation, they are accessibly disposed in the atmosphere, being herein shown to be applied on the under sides of the action bars, although obviously these action bars may face in any direction, according to the convenience or preference of the organ designer or builder. The opposing forces acting upon each of these levers comprise on one hand variable pneumatic pressure acting through a primary pneumatic 4 upon one portion of the lever, and on the other hand, the tension or pressure of a spring acting against another portion of the lever. Thus these forces are indirectly opposed in the sense that they are applied to different points or portions of the lever. When no air is being admitted to the vacuum chamber 5 through the tracker board or otherwise, the lever is held in its inactive position shown in Fig. 1 by the predominance of the atmospheric pressure against the outer side of the pneumatic pouch 4, which overcomes the tension of the spring 18, thus holding the contacts 25 and 26 away from their respective coating terminal contacts 27 and 28. A slight flushing of the pneumatic 4, due to the passage of one of the smaller perforations 15 over its tracker duct partially counterbalances the atmospheric pressure upon the pneumatic, and thus inaugurates the first phase movement of the lever, allowing its least resisting left hand end to be drawn down by the spring 18, thus closing the contacts 25 and 27 and sounding whatever note may be associated therewith. Meanwhile, the atmospheric pressure against the pouch 4 remains sufficiently strong to hold the right hand end of the lever, to which it is nearest, thus keeping

the contacts 26 and 28 open. A stronger flushing of the pneumatic 4 caused by one of the larger perforations 16 passing over the tracker duct, further weakens the vacuum in the chamber, and thereby inaugurates the second of the two-phase movements of the lever. The weakening allows the spring 18 to overcome the atmospheric pressure and thus to move the right hand end of the lever to its position shown in Fig. 3, thereby closing the contacts 26 and 28 and sounding their associated pipe, which is generally of the same pitch as that controlled by the left hand end of the lever, and is also generally in a different stop or register.

For conciseness and definiteness of expression, the two-part or two-step or two-period action of the lever is herein designated its "two-phase" movement. For the same purpose, the term "indirectly opposed" is employed to designate the action or relation to the lever of the opposing spring and pneumatic forces which act upon it at different portions of its length. As will be evident from the modifications shown in the drawings, the relation and application of these forces may be varied according to circumstances.

In the arrangement shown in Figs. 1 to 9 inclusive the springs 18 are shown to be connected to the levers about midway of their length, while the point of connection of the primary pneumatic is about one-third of the length of the lever from one of its ends. The lower ends of the springs are connected to tension bars 19, which as shown in Figs. 4, 6 and 7 are supported beneath the levers by means of rods 20 attached to any convenient portion of the instrument. These bars extend transversely of the levers, being made in any length which may be found convenient; and are therefore common to a number of the levers. As a means for adjusting each spring independently of the others their lower ends are connected to removable pins 21, which extend through suitable holes in the tension bar 19. The springs extend through holes in the tension bar and the pins are pushed between any coils of the spring, according to the tension desired, the tension of each spring being thus easily adjusted by withdrawing the pin, stretching the spring to the desired tension and replacing the pin to hold it at that tension. These adjustments may be advantageously made while the organ is in operation.

The springs should be adjusted so as to move their respective levers with suitable rapidity when the primary pneumatics are flushed, while allowing the pull of the spring to be overcome by the primary pneumatic when the latter is again exhausted of air. Cushions 22 are preferably provided be-

tween the levers 14 and the face of the action bar. These cushions may be the ordinary disk pallets like the pallets 41 of Fig. 5. They serve to cushion the closing movements of the key levers. As thus arranged, the action of the opposing forces is to draw down the longer end of the lever or the end farthest from the pneumatic when the latter is only lightly flushed, as for example, through one of the small note sheet perforations 15, the other end of the lever being still held in its resting position, due to the balance of the forces at that time; the vacuum although lessened by the partial flushing of the pneumatic being sufficiently strong to hold up that end of the lever against the tension of the spring. A more complete flushing of the primary pneumatic, as for example, through one of the larger perforations 16 of the note sheet, allows the lever to yield entirely to the tension of the spring, which therefore moves the lever to the position shown in Fig. 3.

The first phase of movement operates only the note sounding connections, whether electrical or pneumatic, at the longer and freer end of the lever, whereas the second phase movement operates the note-sounding connections at the other or shorter end of the lever. This second phase movement may leave both ends of the lever in operative positions, as shown in Fig. 3, or it may be made to restore the first moving end of the lever to its initial resting position, as shown in Fig. 2, for the purposes and by the means hereinafter described.

When adapted for electrical connections, as shown in Figs. 1 and 2, the key levers 14 are provided with contacts 25 and 26, which coact with terminal contacts 27 and 28 of branch electric circuits, leading to suitable electro-magnets 29 or solenoids, or other suitable electrically operated agencies which in turn operate either directly or by suitable relay systems, the note sounding devices of the different pipes which are to be operated by the respective levers. In Fig. 1 is illustrated a suitable arrangement for a pair of branch circuits thus controlled by the two contacts carried by the lever 14. In this instance these circuits are completed through a conductor 30 mounted on the lever and electrically connecting its contacts 25 and 26 with the tension spring 18, which is thus utilized as an electric conductor in addition to its mechanical function of a spring. The tension bar 19 to which the lower ends of the springs are connected, may be of conducting material and thus serve also the additional function of a common conductor for the series of springs. In that case each bar has attached to it battery wires 31 connecting with the batteries 32 beyond which the line wires 33 extend and are joined at

intervals by branch circuit wires 34 from the respective electro-magnets 29. The latter are herein shown as electro-pneumatics, the magnets serving when energized by the closing of their respective contacts by the movements of the lever 14 to lift the pallets 35, thus flushing the pipes 36 leading to any suitable note sounding devices for other pipes.

When adapted for pneumatic service, as illustrated in Figs. 5 and 6, the levers 40 are provided with pallets 41 and 42 for closing the openings of the ducts or windways 43 and 44, which lead to suitable note sounding devices either directly or through a suitable relay system, which may be of ordinary and well-known construction, and therefore is not illustrated herein. The construction of the action bar 46, vacuum chamber 47, tracker ducts 48 and primary pneumatic 49 is similar to the corresponding parts shown in Figs. 1 and 2 and already described, except for the addition of the windways 43 and 44 and the stops 50, which in the absence of the contact wires shown in the other figures are employed for limiting the opening movement of the ends of the levers. The construction, mechanical function and mode of operation of the lever springs 18, tension bar 19, and adjusting pins 21 are the same as those previously described in connection with Fig. 1. These levers 40 are operated by variations in the balance of the opposing forces influenced by different pneumatic impulses admitted through the tracker ducts 48 from a note sheet having different sized perforations, as already described in connection with Fig. 1. The slighter impulse, due to the partial flushing of the primary pneumatic through a small perforation, allows the primary to be overcome by the tension of the spring, which therefore opens the least resisting left hand end of the lever 40, thus lifting the pallet 41 at that end, and opening the windway 43. The stronger impulse admitted through the larger sized perforation allows the spring to draw both ends of the lever in close succession down against their respective stops, thus also opening the right hand windway 44 and operating the note sounding device to which it leads.

The arrangement shown in Figs. 7, 8 and 9 is adapted for both electric and pneumatic connections for the lever, being in effect a combination of the two systems shown in the previous figures, each lever being thus adapted to serve four connections, two at each end, to four different note sounding devices. The action bar 55, its tracker ducts 56, pneumatic 57, branch contacts 58 and 59, windways 60 and 61 and stops 62 are similar in construction and mode of operation to those previously described. The lever 64 is provided with

42
pallets 65 and 66 and spring 18 leading to the tension bar 19 like those described in connection with the previous figures; and is also provided with contacts 67 and 68 and a conducting wire or strip 69, like those shown and described in connection with Fig. 1, and operating the same way. This in fact is a convertible form of action, enabling the electrical connections to be used or not, as may be desired. The conversion may be made by adjusting the branch contacts 58 and 59 vertically, or by adding or removing the stops 62. To put the electric system into operation it is only necessary to adjust the branch circuits 58 and 59 upwardly so that the movement of the levers 64 will make contact before striking the stops 62; or by removing those stops altogether, in which latter case the branch contacts also serve as stops for the opening movement of the lever.

Fig. 7 also illustrates further details of an approved form and arrangement of the action bar. The vacuum chamber 71, extending lengthwise of the bar, connects at one end by means of a pipe 72 with a pump or other suitable means for producing the required vacuum. A regulating device for equalizing the tension of the vacuum in the chamber is also shown in this figure, consisting of a diaphragm 73 disposed in a pocket 74 or reservoir, communicating by means of a passage 75 with the vacuum 71. The diaphragm 73 is held outwardly against the atmospheric pressure induced by the vacuum by means of a spring 76, the tension of which serves to maintain the vacuum at approximately uniform tension.

In some instances it may be found desirable to avoid concurrent sounding of the notes controlled by the two ends of the levers, due to closing the two branch circuits at the two ends of the lever 14, as shown in Fig. 3; or due to opening both of the windways 60 and 61 as shown in Fig. 9. To avoid this a movable fulcrum 80 is mounted adjacent to the levers, as shown in the various figures, which when applied converts the second phase movement of the lever into a swinging movement, which by closing the pallet or by opening the contact operated by the initial or first-phase movement of the lever, stops the sound of the pipe or pipes controlled by that end of the lever. The movable fulcrum 80 is herein shown as a rod extending transversely along the underside of all, or any desired number of the levers. The ends of the rod are mounted in rocker arms or plates 81, which are pivoted at 82 to any convenient portion of the frame or console, and are connected by means of a rod 83 with a suitable knob, lever, or tablet 84 conveniently adjacent to the keyboard or else-

where within convenient reach of the organist. When these fulcrum rods are moved to their off position shown in Figs. 3 and 9, the notes controlled by both ends of the levers effected will be sounded concurrently. But when moved to the "on" position shown in Figs. 2, 5 and 8, the lever will, after sounding the note controlled by the first phase of its movement, shut off that note by the second phase of its movement.

Fig. 10 illustrates a modification of the invention adapted for electrical connection with note sounding devices. This modification is also shown to be adapted for operation by a pressure system instead of the vacuum system illustrated in the previous figures, although this may obviously be adapted also to a vacuum system. The action bar 87, adapted for receiving any desired number of these actions disposed side by side along the length of the bar, is provided with the primary pneumatic 88 connecting by means of the duct 89 with a pressure wind chest, and by means of a tracker duct 90 with a tracker board controlled by a note sheet as illustrated in the previous figures. The lever 91 in this instance is shown as a contact wire, having an insulated connection with the primary pneumatic 88. This wire is made of spring metal having an upward set tending to close the pneumatic when the pressure behind it is released by the escape of the air through an aperture of the note sheet. The escape of air through a small aperture weakens the pressure sufficiently to allow the spring of the lever to make contact with a battery terminal 92, which is electrically extended to the battery 93. The opposite pole of the battery is connected by means of the line wire 94 and branch wire 95 with a solenoid 96 or other agency for energizing or operating note sounding devices of the pipe thus controlled by the initial or first-phase of the movement of the lever 91, which is also electrically extended by means of the wire 97 to solenoid 96, to complete the circuit. A more complete release of the pressure from the pneumatic, through a larger perforation of the note sheet allows a more complete collapse of the pneumatic under the continued pressure of the resilient lever 91, the continued movement of which carries the resilient battery terminal 92 against the other branch terminal 98, which connects with a similar solenoid 99, the circuit of which is completed through the branch circuit wire 100, leading to the line wire 94, which is common to any desired number of these branch circuits served by the battery 93.

The arrangement shown herein may be adjusted for operation by a vacuum system like that shown in the previous figures, merely by

transposing the positions of the end of the lever 91 and the branch contact 98, disposing the lever above and the branch circuit 98 below the battery terminal 92, without any other change, except of course to substitute a partial vacuum for the pressure in the chamber to which the duct 89 leads.

Figs. 11, 12 and 13 show a further modification, also operated by a pressure system, having pneumatic connections for the note sounding devices. In this, as in the modification previously described, both note sounding connections are made at one end of the lever, instead of being at opposite ends, as in Figs. 1 to 9 inclusive. The action bar 105 carrying a desired number of these actions, is provided with a pneumatic 106 for each lever 107 communicating by means of the duct 108 with a wind chest and by means of the tracker duct 109 with a tracker board operated by a perforated note sheet, as in the previous figures. One end of the lever 107 is pivoted at 110 to the action bar, being held in place by any suitable means, as for example by the spring 111, which by varying the point of its application to the lever, relative to the pivot 110, is or may be adapted not only to hold the pivotal connection in place, but to serve also as the spring for operating the lever. Or any desired form of spring 112 may be applied to the lever whenever required, pressing upwardly in connection with the pressure system illustrated in these figures. The opposite end of the lever 113 is provided with a pallet 114, closing the windway 115, leading to the note sounding devices of the pipe to be operated by the initial or first-phase movement of the lever. A secondary lever 116, carrying a pallet 117, which closes the windway 118 leading to the note sounding devices of the pipe to be controlled by the second-phase movement of the lever, is disposed above and in the pathway of the end of the lever, being held in its closed or resting position by means of a spring 119. The passage of one of the smaller perforations of the note sheet over the tracker duct 109 releases the pressure above the pneumatic sufficiently to allow the lever with its pallet to be raised by the spring until it stops against the secondary lever 116, as shown in Fig. 12, thus opening the windway 115 and sounding the note controlled by the initial or first-phase movement. A more complete release of the pressure above the pneumatic due to the passage of one of the larger perforations of the note sheet over the tracker allows the key lever to be moved by its spring with sufficient force to move the secondary lever 116 and thus open the windway 118, thereby sounding the note controlled by the second-phase movement of the lever, as illustrated in Fig. 13.

In order to adapt the modification shown

in Figs. 11, 12 and 13 to a vacuum system like that illustrated in Figs. 1 to 9 inclusive, it is only necessary to invert and transpose the position of the windways 115 and 118 and the secondary pallet lever 116, and to apply the spring of the lever so as to draw it downwardly as shown in Figs. 1 and 5, instead of pressing it upwardly. In many other ways which will be obvious to those familiar with this art, the construction, or arrangement of the parts may be modified, transposed, inverted or otherwise reversed to suit various requirements or different conditions.

Among the important and useful features of this invention are its extended capacity of control, the simplicity of its parts, and their accessibility for inspection, adjustment and repairs, while under actual working conditions, when the organ is in full operation, without having to enter a wind chest or action chamber, in which a pressure above or below that of the atmosphere is maintained, this latter advantage being due to the fact that these actions are accessibly disposed in the atmosphere.

90 I claim as my invention:—

1. An organ action, including in combination an air chamber, a lever disposed outside of the air chamber and provided with means for controlling a plurality of note-sounding connections, a pneumatic motor communicating with the air chamber, and connected with the lever, and means for controlling the lever by admitting pneumatic impulses of different strength to the air chamber side of the motor.

2. An organ action, including in combination a lever accessibly disposed in atmospheric pressure, a plurality of note sounding connections controlled by the lever, a pneumatic motor connected with the lever and exposed to different pressures on its opposite sides, means for admitting pneumatic impulses of different strength to one side of the motor, and resilient means also accessibly disposed in the atmosphere and co-operating with the said pneumatic impulses to move the lever.

3. An organ action, including in combination a lever provided with a plurality of note sounding connections accessibly disposed in atmospheric pressure, a tracker duct, a pneumatic motor connected with the lever and exposed on one side to atmospheric pressure, and on the other side to varying pneumatic pressures through the tracker duct, and means for controlling the duct to impart to the motor pneumatic impulses of differing strength.

4. An organ action, including in combination a lever accessibly disposed in atmospheric pressure, a plurality of note-sounding connections for the lever, a tracker duct, a

pneumatic motor connected with the lever and exposed on one side to atmospheric pressure, and on the other side to varying pressures controlled through the tracker duct, 5 and resilient means for partially balancing the said atmospheric pressure on one side of the motor.

5. An organ action, including in combination a lever accessibly disposed in atmospheric pressure, a plurality of note-sounding connections for the lever, a tracker duct, a pneumatic motor connected with the lever and exposed on one side to atmospheric pressure and on the other side to varying pressures controlled through the tracker duct, 10 resilient means for partially balancing the said atmospheric pressure on one side of the motor, and means for controlling the tracker duct to communicate pneumatic impulses of 15 varying strength to the motor.

6. An organ action, including in combination a lever accessibly disposed in atmospheric pressure, a plurality of note-sounding connections for the lever, a pneumatic motor connected with the lever and exposed on one side to atmospheric pressure, means including a tracker duct for communicating pneumatic impulses of varying strength below atmospheric pressure to the other side of the 20 motor in opposition to the atmospheric pressure, and a spring coöoperating with the said impulses for operating the lever.

7. An organ action, including in combination a lever provided with a plurality of note sounding connections and accessibly disposed in atmospheric pressure, a pneumatic motor connected with the lever, and exposed to atmospheric pressure on one side and to varying pressures on the other side, resilient 35 means applied to the lever at a different point from the connection between the lever and the motor, and in opposition to the said atmospheric pressure upon one side of the motor, whereby a two-phase movement is 40 imparted to the lever by the coöperation of the pneumatic motor and the resilient means.

8. An organ action, including in combination a lever provided with a plurality of note sounding connections and accessibly disposed in atmospheric pressure, a pneumatic motor connected with the lever for holding the lever in inoperative position relative to its note sounding devices, and resilient means also disposed in atmospheric pressure and 50 acting in opposition thereto to operate the lever against the atmospheric pressure on the motor, the resilient means and the pneumatic motor being applied at different points in the length of the lever whereby one of the 55 said note-sounding connections is operated in advance of the other note-sounding connection.

9. Organ actions, including in combination a vacuum chamber, a series of levers

accessibly disposed outside the chamber, 65 pouch pneumatics connecting the respective levers with the wall of the chamber, and air ducts communicating through the said wall from the said pneumatics to the chamber and to tracker openings.

70

10. Organ actions, including in combination a vacuum chamber, a series of levers accessibly disposed outside the chamber, pouch pneumatics attached at their edges to the wall of the chamber and attached at 75 their centers to the said levers, and air ducts communicating through the said wall from the said pneumatics to the said chamber and to tracker openings.

11. Organ actions, including in combination a vacuum chamber, a series of levers supported on the outer side of a wall of the vacuum chamber, a separate pneumatic motor attached to each of the levers and exposed on one side to atmospheric pressure, 80 a spring for each motor opposing the atmospheric pressure thereon, and air ducts communicating from the motors to the vacuum chamber and terminating in tracker openings.

85

12. Organ actions, including in combination a vacuum chamber, a series of levers supported on the outer side of a wall of the vacuum chamber, pneumatic motors for the levers also supported on to the outer side of 95 the wall and exposed on one side to atmospheric pressure, a spring for each motor, opposing the atmospheric pressure thereon, air ducts extending from the vacuum chamber to the insides of the respective motors, 100 and tracker ducts leading from said air ducts for admitting air to said ducts to weaken the vacuum in the ducts.

95

13. Organ actions, including in combination a vacuum chamber, a series of levers 105 disposed side by side in the atmosphere, pneumatic motors attaching the respective levers to a wall of the chamber and exposed on one side to atmospheric pressure, a spring 110 for each motor opposing the atmospheric pressure thereon, air ducts communicating from the vacuum chamber to the respective motors, tracker ducts connecting the said air ducts with a tracker, and a note sheet having different sized perforations for admitting different amounts of air to weaken the vacuum in the air ducts.

110

14. An action for organs, including in combination a lever provided with a plurality of note-sounding connections, and a 115 pneumatic motor connected with the lever and exposed to atmospheric pressure on one side, and exposed to variable pneumatic impulses on the other side.

120

15. An organ action, including in combination a lever provided with a plurality of note sounding connections, a pneumatic motor connected with the lever on one side and

125

exposed to variable pneumatic impulses on the other side, and means for resiliently assisting the said pneumatic impulses in operating the lever.

5 16. An organ action, including in combination a lever having a plurality of note sounding connections, a pneumatic connected with the lever and exposed to atmospheric pressure on one side, and exposed to 10 a varying vacuum on the other side, and resilient means connected with the lever for opposing the atmospheric pressure coöperating with the said varying vacuum to actuate the lever to make its note-sounding connections.

15 17. An organ action, including in combination a lever accessibly disposed in the atmosphere and provided with a plurality of connections for note sounding devices, a 20 pneumatic motor and a spring for moving the lever, and adjustable means also accessibly disposed in the atmosphere for varying the tension of the spring.

18. An organ action, including in combination 25 a lever accessibly disposed in the atmosphere and provided with a plurality of connections for note sounding devices, a pneumatic motor and a spring acting upon the lever in different directions, and means 30 also accessibly disposed in the atmosphere for adjusting the tension of the spring.

19. An organ action, including in combination a lever accessibly disposed in the atmosphere, a plurality of note-sounding connections 35 for the lever, a pneumatic motor, and a spring connected with the lever in opposed relation to each other, and means also accessibly disposed in the atmosphere for adjusting the tension of the spring to 40 increase or diminish the strength of its opposition to the motor.

20. An organ action, including in combination a lever provided with a plurality of note sounding connections, means for imparting successive movements to the lever and a fulcrum movable into and out of position for converting movement of the lever into a reverse movement at one end of the lever.

50 21. An organ action, including in combination a lever provided with a plurality of note sounding connections, means for imparting successive movements to the lever, and a fulcrum movable into and out of its 55 fulcrum position for converting movement of the lever into a swinging movement upon the said fulcrum, whereby the first note-sounding connection may be rendered inoperative upon the operation of the second 60 note sounding connection.

22. An organ action, including in combination a lever having a plurality of note sounding connections, means for imparting two-phase movements to the lever, and a

fulcrum disposed between the said note 65 sounding connections of the lever and movable into its fulcrum position whereby the second phase movement of the lever may be converted into a swinging movement, putting one of said note sounding connections 70 into and the other out of operation.

23. Organ actions, including in combination an action bar, a series of levers attached to one side of the action bar, and accessibly disposed in the atmosphere, pneumatic 75 motors for the respective levers attached to the same side of the action bar, and exposed to atmospheric pressure on one side, a vacuum chamber upon another side of the action bar, and a series of air ducts communicating 80 through the bar from the vacuum chamber to the other sides of the respective pneumatic motors and terminating in tracker openings.

24. Organ actions, including in combination an action bar, a series of levers disposed upon one side of the bar and provided with a plurality of note sounding connections, a vacuum chamber upon the opposite side of the bar, a series of pneumatics acting 90 on the respective levers, and a series of air ducts communicating from the respective pneumatics to the vacuum chamber.

25. Organ actions, including in combination an action bar, a series of levers disposed 95 in the atmosphere on one side of the bar and provided with a plurality of note sounding connections, a vacuum chamber upon the opposite side of the bar, pneumatic motors connected to the respective levers, and air 100 ducts communicating through the bar from the vacuum chamber to the respective motors.

26. An organ action, including in combination an action bar, a series of levers disposed side by side in the atmosphere adjacent to one side of the bar, note sounding connections appurtenant to the ends of the levers and to the bar, a vacuum chamber appurtenant to the bar, pneumatic motors for 110 the respective levers, air ducts communicating from the said motor to the vacuum chamber, and tracker ducts leading from said air ducts for admitting air to weaken the vacuum in the said ducts.

115 27. The combination, in organ actions, of an electric circuit, a lever with electrical connections controlling a note sounding device in the circuit, and means for moving the lever, including a tension bar in the circuit, 120 and a spring electrically and mechanically connecting the tension bar with the lever.

28. The combination, in organ actions, of an electric circuit, a lever electrically connecting a note sounding device in the circuit, 125 and mechanical means for moving the lever, including a spring and a tension bar of conducting material in the circuit, mechanically

and electrically connecting the said lever in the circuit.

29. The combination, in organ actions, of an electric circuit, a plurality of levers provided with electrical connections in the circuit for controlling note sounding devices, pneumatic means for moving the levers in one direction, and means for electrically connecting the levers in the circuit, and 10 mechanically moving them in opposition to their pneumatic means, including a tension bar of conducting material in the circuit,

common to the plurality of levers, and springs of conducting material connecting the tension bar with the respective levers. 15

In testimony whereof I have signed my name to this specification in the presence of two subscribing witnesses, this 27th day of July, 1911.

JOHN T. AUSTIN.

Witnesses:

KARL E. PEILER,
CAROLINE M. BRECKLE.

Corrections in Letters Patent No. 1,107,130.

It is hereby certified that in Letters Patent No. 1,107,130, granted August 11, 1914, upon the application of John T. Austin, of Hartford, Connecticut, for an improvement in "Organ-Actions," errors appear in the printed specification requiring correction as follows: Page 6, line 95, strike out the word "to"; page 7, line 112, for the word "motor" read *motors*; and that the said Letters Patent should be read with these corrections therein that the same may conform to the record of the case in the Patent Office.

Signed and sealed this 20th day of October, A. D., 1914.

[SEAL.]

J. T. NEWTON,

Acting Commissioner of Patents.
